his Attorney.

UNITED STATES PATENT OFFICE.

OSCAR KROEHL, OF LAKewood, OHIO.

SIGNAL LENS.

Application filed January 10, 1921. Serial No. 436,083.

To all whom it may concern:

Be it known that I, OSCAR KROEHL, a citizen of the United States, residing at Lakewood, in the county of Cuyahoga and 5 State of Ohio, have invented a new and useful Signal Lens, of which the following is a specification.

This invention relates to improvements in signal-lenses, and pertains more especially 10 to a signal-lens which has its outer side or front comprising spaced light-transmitting portions and substantially opaque surfaces extending between said light-transmitting portions, and which is to be employed in 15 forming the face of a stop-signalling lamp adapted to be carried by and face rearwardly of a motor-vehicle, for the purpose of indicating or signalling, to drivers of following vehicles, that the movement of the signalling 20 vehicle is about to be arrested or checked.

The primary object of this invention is to render an artificially illuminable signal-lens distinctly visible at an adequate distance, in the daytime as well as at night, as a 25 danger-signal and for signalling to drivers of following conveyances that the signalling vehicle is about to come to a stop.

Another object is to produce a signal-lens the front of which comprises spaced light- 30 transmitting portions of danger-indicating color and of the configuration required to form a sign, and also comprises a light-transmitting portion having a danger-indicating color and extending circumferentially 35 of and spaced from said sign, and has substantially opaque surfaces extending between said light-transmitting portions, so that said light-transmitting portions are rendered conspicuous as required to display a danger-indicating sign, and danger-indicating light 40 upon the required artificial illumination of the lens at its inner side or back.

Another object is to have the hereinbefore mentioned light-transmitting portions 45 of the front of the lens, when the lens is properly artificially illuminated at its back, distinctly visible at an adequate distance at any hour of the day and in all kinds of weather, and more especially to have said 50 light-transmitting portions and the hereinbefore mentioned sign, upon said illumination of the lens, effective when they are directly exposed to light-rays from the sun.

Another object is to so form the back of 55 the lens that said back has substantially all of its portions which are behind the herein-

before mentioned colored light-transmitting portions of the front of the lens provided with rearwardly flaring cavities so that, in transmitting light from said back to said 60 light-transmitting portions by the required artificial illumination of the lens at said back, light-rays are so refracted and diffused at the surrounding walls of said cavities as to effect the production, at said front 65 of the lens, of a glow of highly brilliant colored light which is distinctly visible at an adequate distance from the lens in the day-time as well as at night and even when said light-transmitting portions are exposed 70 directly to light-rays from the sun.

Another object is to so form my improved lens that it can be produced with facility and at a low cost.

With these objects in view, and to attain 75 any other object hereinafter appearing, this invention consists in such configuration or features, and combinations and relative arrangements of the different portions of the lens, hereinafter described in this specification, pointed out in the claims, and illustrated in the accompanying drawings.

In said drawings, Figure 1 is a front view of my improved lens. Figs. 2 and 3 are sections taken along the line 2—2 and line 85 3—3, respectively, of Fig. 1, looking in the directions indicated by the arrows. Fig. 4 is a back view of the lens.

Said lens comprises a glass plate 7 which is preferably circular and adapted to be 90 placed in a substantially vertical position in forming the face of a stop-signalling lamp adapted to be carried by, and face rearwardly of, a motor-vehicle, for the purpose of indicating or signalling to drivers of following vehicles, upon the required artificial illumination of the lens in any approved manner at the back of the lens, that the movement of the signalling vehicle is about 95 to be arrested or checked.

The front of the lens is shown as comprising an inner circular face the circumference of which is indicated by the reference-character 8 in Fig. 1. Said front also comprises an outer forwardly facing 105 annular and substantially plane surface 9 which is concentric in relation to the aforesaid inner face. Preferably the lens has its outer portion, which comprises the annular surface 9, projecting, as at 10, somewhat 110 forwardly of the body of the lens. The surface 9 forms the face of the projecting

annular portion 10, and preferably said projecting portion has its internal diameter measuring over three inches.

The front of the lens is shown provided 5 within the space surrounded by the projecting portion 10, with spaced forwardly projecting portions 12 which have substantially plane faces and are such in number, configuration and relative arrangement as to 10 form the letters S, T, O and P in the order required to form the sign "Stop." Preferably the annular surface 9 and the faces of 15 the sign-forming portions 12 are substantially in the same plane, and the projecting portion 10 surrounds and is spaced from said sign.

The projecting portions 10 and 12 are light-transmitting and of red or danger-indicating color. Between the sign-forming 20 portions 12 and between the annular portion 10 and said sign-forming portions extend forwardly facing surfaces 13. Preferably my improved lens comprises a plate of light-transmitting red glass blackened and thereby 25 rendered opaque at the front of the lens between the sign-forming projecting portions 12 and between the projecting annular portions 10 and said sign-forming portions, so that, upon the required artificial illumination 30 of the lens at its back, light is not transmitted by the surfaces between said sign-forming portions, nor by the surfaces between the annular surface 9 and said sign-forming portions.

35 The back of the lens has substantially all of its portion which is behind the front annular surface 9 of the lens provided with rearwardly flaring and preferably segmentally spherical cavities 15, and preferably 40 said cavities are such in dimensions and number that each cavity 15 measures substantially one-eighth of an inch in diameter at its diametrically larger end and that at least forty cavities 15 are formed in the 45 lens per square inch of the area of said portion of the back of the lens.

Also, the back of the lens has substantially all of its portions which are behind the sign-forming portions 12 of the front 50 of the lens provided with rearwardly flaring and preferably segmentally spherical cavities 16, and preferably said cavities 16 are such in dimensions and number that each cavity 16 measures substantially one-eighth 55 of an inch in diameter at its diametrically larger end, and that adjacent cavities 16 are in close proximity to each other.

I would here remark that, in a lens embodying my invention and having the meritorious features or characteristics hereinbefore described and illustrated in the accompanying drawings, light-rays are so refracted and diffused at the surrounding walls of the rearwardly flaring cavities 15 and 16, upon 60 the required illumination of the lens by the

use of a conventional reflector placed opposite and spaced from the back of the lens with an incandescent bulb between the reflector and the lens, that an effective danger-indicating light and the hereinbefore mentioned sign are distinctly visible at an adequate distance from the lens in the daytime as well as at night. The chief function of the concavities on the rear face of the lens is to cause intense rays to be directed through 70 the transparent portions on the front face not only directly rearwardly but laterally as well. In fact each concavity forms in effect a focal point from which intense light rays are spread so that the signal stands 75 out sharply and is strongly visible to the eye of a person located not only behind but to the side of the rear of the lens and the further effect is to make it possible to plainly 80 see the signal quite a distance from the lens 85 in day light as well as in the night and in foggy as well as in clear weather.

What I claim is—

1. A lens for a signal lamp comprising a plate having translucent and opaque portions the former arranged to form a visual signal and the plate having the rear substantially flat face with light directing surface irregularities. 90

2. A lens for a signal lamp comprising a plate having translucent and opaque portions, the former arranged to form a visual signal and said plate having on the rear face closely arranged minor indentations and projections lying in the same general 100 plane. 95

3. A lens for a signal lamp comprising a plate having translucent and opaque portions, the former arranged to form a visual signal and the plate having a rear substantially flat face with closely arranged minor concavities. 105

4. A lens for a signal lamp comprising a translucent plate having a front face with portions through which light rays may pass and arranged to form a signal and with other portions treated to render the same opaque, and said plate having a rear substantially flat face with light directing surface irregularities. 110

5. A lens for a signal lamp comprising a translucent plate having a front face with portions through which light rays may pass and arranged to form a signal and with other portions treated to render the same opaque and said plate having a rear face provided with closely arranged alternate depressed and elevated portions forming surface irregularities lying in the same general plane. 120

6. A lens for a signal lamp comprising a translucent plate having a front face with portions through which light rays may pass and arranged to form a signal and with other portions treated to render the same 125 130

opaque and said plate having a rear substantially flat face with closely arranged or contiguous small concavities.

7. A lens for a signal lamp comprising a translucent plate having on the front face sign forming portions, the remainder of the plate being opaque, and means on the rear surface of said plate for receiving and directing rays of light through the sign forming portions in lines or directions inclined to the surface of the plate.

8. A lens for a signal lamp comprising a flat plate of translucent material having on the front face protruding portions through which light rays may pass and arranged to form a signal, said portions being surrounded by a relatively depressed surface treated so as to be relatively opaque, said protruding portions having plane or flat outer faces.

9. A lens for a signal lamp comprising a plate of translucent material having a substantially flat rear face and having on the front face protruding portions arranged so as to constitute a signal and outside of said portions a peripheral protruding portion adapted to engage the attention of the observer, all said protruding portions being pervious to light rays and being joined by a relatively depressed surface rendered opaque.

10. A signal-lens comprising a glass plate having a front which comprises forwardly projecting light-transmitting portions forming a sign and of danger-indicating color

and also comprises a forwardly projecting light-transmitting portion extending circumferentially of said sign and of danger-indicating color, said front having substantially opaque surfaces extending between the light-transmitting portions of the front, and the back of the lens having substantially all of its portions which are behind said light-transmitting portions provided with rearwardly flaring cavities which have a depth centrally of substantially a sixteenth of an inch and a diameter of substantially one eighth of an inch at their diametrically larger ends.

11. A lens for a signal lamp having translucent and opaque portions, said translucent portions being of danger indicating color and arranged to form a visual signal, the translucent signal forming portions of the lens having substantially flat rear faces provided with closely associated light directing surface irregularities.

12. A lens for a signal lamp comprising a translucent plate of danger indicating color, said plate having an opaque covering over a portion of the surface thereof, the remaining uncovered portions forming a visual signal, the signal forming portions having substantially flat rear faces provided with closely associated light directing surface irregularities.

In testimony whereof, I sign the foregoing specification, this 3rd day of January, 1921.

OSCAR KROEHLER.
